[57] CLAIM

The ornamental design for a seat for a stool, as shown and described.

DESCRIPTION

FIG. 1 is a perspective view of the seat for a stool showing my new design;

FIG. 2 is a side elevational view of the seat for a stool of FIG. 1, the opposite side being a mirror image thereof;

FIG. 3 is an auxiliary side elevational view taken approximately 45° offset from the side elevational view of FIG. 2, the opposite side being a mirror image thereof;

FIG. 4 is a top plan view of the seat for a stool shown in FIG. 1; and,

FIG. 5 is a bottom plan view of the seat for a stool shown in FIG. 1.

The broken line showing of the remainder of the stool, including the legs and the lateral support bars, is for illustrative purposes only and forms no part of the claimed design.
